UNITED STATES PATENT OFFICE.

CLYDE H. AVERY, OF WINDSOR, VERMONT.

SAFETY-COVER FOR GONDOLA CARS.

1,182,616.

Specification of Letters Patent.

Patented May 9, 1916.

Application filed May 11, 1915. Serial No. 27,408.

To all whom it may concern:

Be it known that I, CLYDE H. AVERY, a citizen of the United States, residing at Windsor, in the county of Windsor and 5 State of Vermont, have invented certain new and useful Improvements in Safety-Covers for Gondola Cars, of which the following is a specification.

My present invention relates to a new and 10 improved safety cover for "gondola" cars. It is well known that, in the transportation of cars of this type, especially in certain localities, large quantities of coal or other commodities carried therein are stolen by 15 reason of the fact that the cars are open and unprotected at the top. Numerous attempts have been made to overcome this difficulty by providing various kinds of covers to prevent the entrance of the marauders, yet up 20 until the present time none of these devices have proven successful. The majority of the devices appear to be too heavy, whereby they cannot be easily and quickly operated and by reason of the complicated structure 25 the cost of manufacture is beyond reason.

My present invention has therefore been devised with view of providing a cover that is easily and quickly operable, it being exceedingly light, yet durable, and by reason 30 of its simple construction, it is believed that the same may be manufactured at a comparatively low cost.

Various other objects and advantages will become apparent during the continuance of 35 the following description.

The above and other objects which will become apparent, are accomplished by such means as are shown in their preferred form in the accompanying drawings, described in 40 the following specification and then more specifically pointed out in the appended claims.

In the accompanying drawings wherein like characters designate like parts throughout the several views: Figure 1 is a fragmentary view of a car body of the gondola type, illustrating my invention in connection therewith. Fig. 2 is a view similar to Fig. 1 also illustrating my invention partly in 45 section and partly in elevation. Fig. 3 is a plan view of my invention as it appears in Fig. 1. Fig. 4 is a sectional view taken on line 4—4 of Fig. 3 looking in the direction indicated by the adjacent arrow. Fig. 5 is 50 a sectional view taken on line 5—5 of Fig. 55 3 looking in the direction indicated by the adjacent arrow.

Upon reference to the accompanying drawings it will be recognized that my invention has been illustrated in connection 60 with a car body of the gondola type. However in view of the fact that there are numerous forms of gondola cars, it is to be appreciated that my invention is not limited to use in connection with that form illus- 65 trated.

The car body A includes the slanting end piece B and carries a bolster C of the usual type. The bolster C is supported on a truck D, which carries wheels E for engagement 70 with the respective rails (not shown).

As it is the primary object of my invention to provide a device to form a suitable cover for a car body of this type, I have found it advantageous to arrange this cover 75 in sections which may be operated independently. By arranging the cover in this manner, the same may be easily and quickly operated by one person.

In reducing my invention to practice, the 80 respective end pieces B of the car are provided with suitable frame structures which, carrying a section of reticulated material, form the ends of my improved cover apparatus. In view of the fact that the frame 85 work attached at each end of the car body is of substantially the same construction, only one of the end pieces have been illustrated in the accompanying drawings. This frame work consists of vertical standard 90 portions 10, which may be bent adjacent their lower extremities to form the slightly off-set portions 11. By reason of the specific degree of inclination of the off-set portions 11 it will be recognized that the same 95 may be moved to fit snugly about the end piece B of the car body and may be secured in a rigid position through the medium of the fastening elements 12. The standard 100 portions 10 are connected at their upper ends with a cross piece 13 and bent at a point substantially intermediate its ends so that its central portion is slightly higher than the respective ends. A second cross piece 14 also connects the standard portions 10 at a point appreciably above the upper 105 end of the car body. In order to complete the end piece a section of wire fabric is arranged to extend beneath the cross piece 14 and form vertical sections 15, the respective 110

edges of which terminate at a point adjacent the upper portion of the standards 10 and the respective sides of the cross piece 13. The substantially U-shaped bracing strips 16 are employed to be fixed to the frame work of the end piece through the medium of the fastening elements 17, for the purpose of retaining the edges of the sections of wire fabric and provide a neat and compact structure.

The main cover apparatus consists of pairs of oppositely arranged cover sections which may be of any desired number. In view of the fact that the pairs of cover sections are formed in substantially the same manner, one pair thereof will be described in detail, thus superfluous and double description will be avoided. Each of the two cover sections consists of the spaced apart horizontal members 18 and 19 which are connected adjacent their respective extremities through the medium of the standards 20. The standards 20 are bent at their upper extremities to extend inwardly and slightly upwardly and terminate at a point preferably in the plane of the symmetrical axis of the car body. Other standards, similar to the standards 20, such as indicated by the numeral 21, connect the members 18 and 19 at certain points intermediate the first mentioned standards, with view of providing a more durable structure.

A series of substantially L-shaped arms 22 have connection with the members 18 as at 23, and extend in spaced-apart relation with the standards 20 and 21 respectively. The upper portion of the arms 22 is bent at a point appreciably below the point of bending of the standards 20 and 21, to provide portions 24 which extend parallel with the upper bent portions of the other standards, and terminate in alinement with the respective terminals of the standards 20 and 21.

Links 25 are utilized for connecting the bent portions 24 of the arms 22 and the upper bent portions of the standards 20 and 21, and when the cover sections are in a closed position, these links will lie in the position indicated in Fig. 5. For the purpose of further assuring the rigidity of the cover sections, the reinforcing strips 26 and 27 are arranged to connect the bent portions 24 and the upper bent portions of the standards 20 and 21 at a point adjacent their inner terminus, the adjacent edges of the strips contacting as in Fig. 5, when the cover sections are in a closed position. The hinge elements 28 are fixed to the members 18 and 19 as at 29 and are pivotally connected to the elements 30 which are fixed to the respective side portions of the car body. By this arrangement it will be appreciated that the cover sections are each hingedly connected to the car body, whereby either of the sections may be operated independently, if

it is desired or both of the cover sections manipulated easily and quickly.

The respective cover sections are covered with a suitable reticular material such for instance as wire fabric. The upper edge of the section of wire fabric such as indicated by the numeral 30' is secured beneath the reinforcing strips 27 and brought to extend outwardly and downwardly about the standards 20 and 21. Being brought beneath the lower member 18, the fabric is now continued along the inner faces of the arms 22 and the portions 24 thereof and has its other edge secured beneath the reinforcing strips 26. Thus it will be appreciated that each of the cover sections consists of a double section of fabric which will not increase the weight thereof to any material extent, yet it will greatly add to the efficiency of the device.

The upper bent portions of the standards 20 and 21, of one of the cover sections, are provided with brackets 31 which rigidly support a walking board 32, the latter lying on the reinforcing strips 27 when the cover sections are in a closed position thereby releasing the strain on the brackets. At one end of each of the cover sections are fixed suitable chain elements 33 which may be brought together above the walking board 32. Another chain element 34 is fixed to the cross piece 13 of the end portion of the cover and terminates at a point whereby the locking element 35 may be utilized for the purpose of connecting the same with the chain portions 33.

Thus it will be recognized that the cover sections may be locked in a secure position together with the end piece of the cover thereby preventing the operation of the cover sections by unauthorized persons. Chain elements 36 are carried at the other end of each of the cover sections, and may be connected by a locking member 37 as clearly shown in Fig. 3. With view of limiting the movement of the cover sections when in an open position, the flexible members 38 and 39 are attached at one end to a common hook 40 on the car body and at the other end to the hooks 41 carried on the cover sections. Thus it will be recognized that when the cover sections are drawn outwardly, the flexible members 38 and 39 will be drawn taut and support the same at a suitable angle whereby they may be moved to a closed position quickly and easily.

From the foregoing it will be recognized that my invention consists of a light and durable cover apparatus which, being arranged in sections may be completely controlled by one person.

In reducing my invention to practice I find that the form referred to herein as the most practical and preferred embodiment is the most efficient, but realizing that certain conditions will necessarily vary in con-

currence with the adoption of my device, I desire to emphasize the fact that various minor changes in the details of construction and in the proportion of parts may be 5 sorted to when required without sacrificing any of the advantages of my invention as defined in the appended claims.

Having thus fully described my invention, what I claim as new and desire to set 10 cure by Letters Patent is:

1. In a device of the character described, the combination with an open top car body structure, of a plurality of cover sections hingedly connected thereto, and walking 15 boards carried by certain of said sections and overlying the other of said sections when they are in a closed position, substantially as described.

2. In a device of the character described, 20 the combination with an open top car body structure, of a series of oppositely arranged cover sections hingedly connected thereto, the opposite cover sections engaging each other when in a closed position, at a point 25 in the plane of the longitudinal axis of said car body, means to lock said cover sections in a closed position, and flexible members for limiting the outward movement of said cover sections, substantially as described.

3. In a device of the character described, 30 the combination with an open top car body structure, of a series of oppositely arranged cover sections, the opposite sections engaging each other when in a closed position, 35 brackets secured to certain of said sections, a walking board carried by said brackets, means to lock said cover sections in a closed position and means including flexible members having connection with said car body 40 and said cover sections for the purpose of limiting the amplitude of oscillation of said cover sections, substantially as described.

4. In a device of the character described, 45 the combination with an open top car body, of a series of oppositely arranged cover sections hingedly connected thereto, each of said cover sections consisting of an outer and inner frame work, and a section of reticulated material secured to said outer 50 and inner frame work, for the purpose specified.

5. In a device of the character described, the combination with an open top car body structure, of a series of oppositely arranged

cover sections, opposite sections engaging 55 each other when in a closed position, each of said cover sections consisting of an outer and inner frame work, having a section of reticulated material common to both, means to lock said cover sections in a closed position and means to limit the amplitude of oscillation thereof, substantially as described. 60

6. In a device of the character described, the combination with an open top car body, 65 of a series of oppositely arranged cover sections hingedly connected thereto, opposite cover sections engaging each other when in a closed position, each of said cover sections consisting of an outer and inner frame 70 structure having a section of reticulated material common to both, walking boards carried on certain of said cover sections and resting at the juncture of the opposite cover sections. 75

7. In combination with a car body support, a pair of oppositely arranged cover sections hingedly connected thereto, said cover sections engaging each other when in a closed position, a section of reticulated 80 material covering each of said cover sections, brackets carried on one of said cover sections, a walking board fixed to said brackets and overlying the juncture of said sections, and means to limit the movement 85 of said sections, substantially as described.

8. In a device of the character described, an open top car body structure, a pair of cover sections hingedly connected therewith, each of said cover sections consisting of an outer and inner frame structure, 90 means connecting said frame structures, a section of reticulated material extending about the outer frame structure and also extending about the inner frame structure, a 95 walking board carried on one of said cover sections and overlying the juncture of said sections when they are in a closed position, means to lock said cover sections in a closed position and means to limit the movement 100 of said cover sections.

In testimony whereof I affix my signature in presence of two witnesses.

CLYDE H. AVERY.
